14 Claims. (Cl. 93—6)

1

My invention relates to the formation of air and liquid tight closures in bag tubes, bags, liners and the like. More and more products hitherto packaged in tin or glass or other rigid structures in which hermetic closures could be obtained are now being packaged in sealed bags, and present restrictions on tin and other metals have accelerated the need for efficient hermetic end closures for flexible bags and liners. In many packaging procedures the bags are placed or formed in outer cartons, and one aspect of the problem is the formation of end closures in bags or liners which are already positioned within a carton body. The bags, bag tubes or liners themselves may be formed from a variety of sheetlike materials including those hereinafter set forth. The formation of lengthwise or side seams in these flexible tubular structures is not a serious problem and may be handled in a variety of known ways, although the principles of the present invention may likewise be applied to this problem. In the formation of liquid and gas tight containers the most serious problem is that of obtaining a dependably liquid tight and hermetically sealed end or ends after a flexible open end tubular structure has been formed.

The most effective and widely used approach to this problem at the present time is that of heat sealing. This, of course, involves making the liner of heat sealable substance or of material coated with a thermoplastic. A flexible tubular structure is provided, the inner surface of which at least is of a thermoplastic or heat sealable material, and the end closures are formed by bringing the opposite mouth walls together under heat and pressure to form the end closure. These are, however, a number of difficulties connected with such a procedure, which in the light of the present invention, it is important to note:

1. Where suitable heat sealing substances in film form are available or where the heat sealing layer exists as a coating on another substance such as paper, for example, the film or coating of heat sealable substance has to be very thin and usually is in the neighborhood of $1/1000$ of an inch in thickness. In attempting by the use of heat and pressure to make an end closure in such a package, the flow of the film itself or of a heat sealable coating under the localized heat and pressure of the operation tends to thin out an already thin film at the vital point of sealing, and is frequently productive of pin holes. Some materials, such as moistureproof Cellophane, present this difficulty in an even greater degree. The normally used moistureproof Cellophane consists of a cel-

2

lulose base approximately $1/1000$ of an inch thick coated with a moistureproof heat sealing lacquer film on each side, the total thickness of the film being approximately $1/40,000$ of an inch. So light a surface coating is incapable of providing sufficient sealing medium to assure a dependable transverse end closure particularly in view of the difficulty next to be discussed.

2. Another principal difficulty is a mechanical one, arising from the structure of the tubed liner in view of the thinness of the coating which has just been discussed. A tubed liner is characterized by a longitudinal seam, usually a lapped seam. Great difficulty is encountered in producing a tight end closure at the point where this lengthwise seam crosses the transverse end closure, because the relatively thin heat sealing films do not provide sufficient surplus sealing medium to bridge the gap created by the extra thickness or thicknesses in the lengthwise seam. There is thus a critical point of leakage in such structures which may prevent the production of a hermetic closure.

This problem is still more aggravated when 25 coated Cellophane is laminated to, say, parchment. In that case, the underside of the overlapped seam is about .0025 inch or more thick, i. e. more than 5 times as thick as the total amount of coating on both opposite surfaces of the Cellophane. It has not hitherto been possible to heat-seal such a liner tightly.

3. Under present conditions due to shortages 30 of rubber and other materials, many heat sealing sheetings heretofore employed are no longer available.

4. In the packaging of commodities in sealed 35 liners by present methods the choice of liner materials is unduly limited. In most instances the type of material employed for the liner or bag itself is determined principally by the necessity of providing for heat sealing the ends of the bag. The requirement for heat sealability therefore frequently precludes the use of materials which would provide a better protection to the contents, or which would be less expensive, and sometimes leads to the use of materials definitely undesirable for the particular purpose.

5. A medium which is desirable for sealing 40 purposes is in many cases not suitable for coating or for film formation. By way of example, a type of coating medium having the quality of heat sealability, being sufficiently flexible and having sufficient anchorage to be used on a base such as cellulose acetate, may lack the single 45 vital characteristic of sufficient grease resistance.

Thus in spite of the inherent grease resistance of the acetate base itself, such a coated sheet may not be suitable for fabricating into containers designed to hold grease or liquid oil, or products containing large quantities of oleaginous substances. By way of another example, certain admixtures of microcrystalline or amorphous waxes with synthetic resins may possess every desirable quality needed for the body of a container which is designed to hold grease or shortening, but at the same time such mixtures may not be suitable for use as a coating on a fabric designed for the manufacture of bag tubes, because the material itself is inherently tacky, or because it has qualities which prevent it from being handled readily in automatic machinery. Again the heat-sealable coating on Cellophane is to provide moisture protection as well as to make it possible to heat-seal; but while it does provide moisture protection to a degree, it is soluble in oil, so that, in a container for oil, the oil eventually dissolves the coating material and hence will dissolve the heat-seal joint. Uncoated Cellophane would not be subject to this defect, but could not be heat-sealed.

Parchment or glassine by itself is oil repellent. The long seam can be made leaktight in forming the tube by using the right kind of adhesive to bring this about. For instance, if the parchment is to be used for oil, it will be necessary to use an oil-repellent adhesive; but to make the end joints leaktight using any of these base materials there is no process known unless the sheeting is provided with a heat-sealable oil resistant coating throughout the entire inner surface. In the case of parchment, such coating on the inner surface would serve but one purpose and that is to provide means for heat-sealing the top and bottom joints to bring about a leaktight condition.

Glassine is grease resistant. An exemplary laminated structure is formed of two sheets of glassine laminated with moisture-resistant adhesive, but has no coating on either side. This material could not hitherto be made into a leaktight oil container without having a heat-sealable or oil-resistant coating, co-extensive with the sheet material of which the container is made. By my process this material is made available in uncoated condition.

The principal object of my invention is the provision of means and a method whereby these difficulties and defects are overcome.

One of the objects of my invention is that of rendering the sealing material independent of the base material whereby I may employ that type of base material best suited for the particular service contemplated and that type of sealing material best suited to form a tight closure. This is a mode of attacking the problem far wider in its implications than anything hitherto possible. It not only permits the use of a wide variety of combinations of sheetings and sealing mediums, but it obviates the almost impossible problem of trying to produce a film or a coated sheet which has optimum qualities for protecting the packaged material and at the same time optimum sealing characteristics.

Another object of my invention is the provision of a means and mode of operation permitting the use of the most desirable packaging materials for any given service. Many of these materials are not heat sealable at all, and the result has been that the art has not been able to use them, if at all, otherwise than in a form

coated with some particular sealing substance which may not add to and may sometimes detract from their general utility. Among such materials might be mentioned vegetable parchments, ethyl cellulose and cellulose acetate sheetings. These last mentioned sheetings have excellent resistance to the penetration of fats and oils, and are flexible, sanitary and resistant to dimensional changes due to atmospheric variations. And yet there is at present no commercial use of these sheetings for such vital purposes as the packaging of oils or greases, or other fluids and semi-fluids, for the sole reason that an effective procedure for the formation of hermetic end closures in tubular structures made of these sheetings is lacking.

It is an object of my invention to permit the formation of hermetically sealed packages from any type of film or fabric having desirable qualities for the particular packaging use irrespective of the possession by the fabric itself of heat sealing qualities.

It is an object of my invention to provide for the formation of hermetically sealed bags, liners or similar structures in which the body fabric can be chosen solely from the standpoint of its protective effect on the contents of the package, and without regard to any other qualities, and a sealing medium may be employed which can be chosen as the best one for its function irrespective of its ability to form a self-sustaining film or a coating on the fabric itself which will not interfere with processing operations.

A very vital object of my invention is the provision of means and a method whereby the amount of sealing medium available in the operation of forming a hermetic end closure can be accurately controlled to the amount necessary for the purpose, without regard to any characteristic of the fabric as a whole, and in this connection it is an object of my invention to provide for the use of sufficient sealing medium to overcome the mechanical difficulties hereinabove set forth.

Yet another object of my invention is the provision of a mode and means for sealing bag tubes and similar structures which is applicable to packaging problems requiring the vacuumization of flexible packages or the introduction and retention of special gases for the protection of the packaged materials.

These and other objects of my invention which will be set forth hereinafter or will be apparent to one skilled in the art upon reading these specifications, I accomplish by that procedure and by that construction and arrangement of parts of which I shall now describe certain exemplary embodiments. Reference is made to the drawings wherein:

Figure 21 is a diagrammatic illustration of another mode of treating bag tube ends to open them.

Figure 22 is a partial plan view of a mechanism related to that shown in Figure 1 but indicating the assembly to it of other elements such as those shown in Figures 6 and 10.

Figure 23 is an elevational view corresponding to Figure 22 but showing certain parts in section.

Figure 24 is a detail of means for operating pressure rollers and is related to Figure 23 as indicated by the line 24—24 therein.

Figure 25 is a partial plan view of another means for pressing the treated mouths of liners or bag tubes.

Figure 26 is a sectional view taken along the line 26—26 in Figure 25.

Figure 27 is an enlarged plan view related to the showing of Figure 25.

Figure 28 is a detail of one of the pressing means employed in the apparatus of Figures 25 to 27.

Figure 29 illustrates an initial relationship of a carton body containing a liner tube, and spreading means whereby the liner tube may be elongated.

Figure 30 is a fragmentary perspective view illustrative of the operation of the spreading means.

Figures 31 to 36 inclusive show a series of instrumentalities and indicate the successive operation thereof in pinching together a liner which has been flattened as in Figure 30, opening up the mouth of the liner, introducing sealing material therein, pressing the liner and finally releasing it.

Figure 37 is a partial plan view of a machine suitable for carrying on the operations illustrated in Figures 30 to 36.

Figure 38 is a plan elevational view of a cam plate.

Figure 39 is an enlarged plan view of certain mechanism shown in Figure 37.

Figure 40 is a fragmentary plan view detailing the construction of certain cam followers.

Figure 41 is a sectional view taken along the line 41—41 in Figure 39.

Figure 42 is a fragmentary sectional view taken along the line 42—42 in Figure 39.

Figure 43 is a fragmentary sectional view taken along the line 43—43 in Figure 39.

Figure 44 is a sectional view taken along the broken line 44—44 in Figure 39.

Figure 45 is an elevational view related to Figure 44 as indicated by the line 45—45 in Figure 44.

Figure 46 is a perspective detail of a valve mechanism.

Briefly in the practice of my invention I achieve a closure by pressing the walls of the liner together along a line across the liner mouth but spaced from the actual liner end, then opening up the liner mouth beyond this line of pressure, then introducing between the surfaces to be joined together a sealing medium in such quantities as may be desired, and finally pressing the parts together to form a joint which provides a tight seal. The final pressing accomplishes three purposes: first, it flattens out the adhesive material, thus providing a wide joint. The width depends on the nature and volume of adhesive material used. Second, it causes the molten adhesive to set or cool more quickly. Third, it causes the opposite sides of the mouth to adhere to each other over the entire seam area. Without such pressing of the mouth after the adhesive has been introduced, a seal can be formed, but since the sealing material would be in the form of an irregular mass, it would be difficult to fold the sealed area without throwing an undue strain upon the lining material and so injuring it; also, without the pressure the bond is not secured as tightly and furthermore it also takes considerably longer to cause the adhesive to set or cool.

For reasons indicated above, I shall describe my invention in connection with the formation of end closures in bag tubes which have already been formed, it being understood that the specific embodiments of mechanism and procedure hereinafter described are not to be regarded as limitations upon my invention otherwise than specified in the appended claims.

The bag tubes in connection with which I shall describe my invention may be formed from any suitable material and in any suitable fashion. Normally such bag tubes will be formed by bending the edges of a continuous strip of the desired fabric about a former or mandrel, and effecting a continuous longitudinal seam therein. The formation of this seam may be accomplished in any suitable fashion either by the fusing together of lapped wall portions in a heat sealable fabric or by the use of applied adhesive. The chief difficulties inherent in the production of hermetically sealed bags and liners are not resident in the formation of the longitudinal seam as much as in the formation of end closures for reasons which have already been given. Consequently, I do not detail the various modes for forming the longitudinal seam, and merely state that where a hermetic seal is to be formed in the liner, bag or similar structure, it is usually necessary to provide a longitudinal seam of such char-

acter that any ply which laps another on the interior of the bag tube or liner shall be thoroughly adhered to the overlying ply to the very edge of the interior ply. If this is not done, a channel may be left between the lapping plies in the longitudinal seam of the liner which will pass through the hermetic end seal, thus nullifying the effect of it. Where it is inconvenient to provide for the adhesive juncture of the inner lapping member out to its very edge, any lapping but unsecured edge portion of the inner member may be cut away or notched in that area where the hermetic end closure is to be formed, to the extent that the sealing material forming the end closure will contact the sealing material by which the longitudinal seam was formed.

In the practice of my invention, I am not limited as to the webs, films, or laminated materials which may be employed in manufacturing my liners. The substance mentioned above, and many others may be used, due regard being had for the relationship of their characteristics to the particular materials being packaged. Similarly, I am not limited as to the employable adhesives. I prefer to employ thermoplastic adhesives. The following formulae are given as exemplary merely, and not as limiting.

If the product to be packaged presents a primary problem of moisture or waterproofing, such as milk, fruit juices, etc., the following adhesives may be used:

Formula 1

	Per cent
Piccolyte	70
Vistanex #6	30

Formula 2

	Per cent
Micro-crystalline wax	60
Vistanex #6	15
Vistac	10
Purified wood rosin	15

In the above formulae, Piccolyte is a trade name for a terpene resin manufactured by the Pennsylvania Industrial Chemical Company, Vistanex #6 is a trade name of a polybutene manufactured by Advance Solvents & Chemical Corp., and Vistac is a trade name for an oily hydrocarbon resin made by the same company. Equivalent substances of other makes may be used.

If the product to be packaged presents a primary problem of oil or grease resistance in the liner, I may employ such formulae as the following:

Formula 3

	Per cent
AYAA	60
Dibutyl phthalate	20
Staybellite	20

Formula 4

	Per cent
AYAA	60
Dibutyl phthalate	20
Wood rosin	20

Formula 5

	Per cent
AYAA	60
Dibutyl phthalate	20
Shellac	20

In the above formulae, AYAA is a trade name for a polyvinylacetate resin manufactured by Carbide & Carbon Chemical Corporation, and Staybellite is a hydrogenated rosin sold under this trade name by Hercules Powder Company.

Equivalent substances of other makes may be used.

The adhesives of the formulae given above are thermoplastic. They may be used in forming the longitudinal seam as well as in the process and apparatus hereinafter described.

When a bag tube has been made up in any suitable fashion, it may be cut apart into individual bag lengths, and these individual bag lengths which hereinafter will be referred to by the term liners may be fed automatically or by hand into the machine partially illustrated in Figure 1. Here the liners 1 are gripped and moved along in timed spaced relationship by frictional gripping means 5, 6 on upper and lower traveling chains. These chains may be caused to move in suitable guides 8 and 10 mounted on the machine. Some of the operations hereinafter described require timing of the liners, and to this end the position of the liners may be determined by suitable pins (not shown) on the lower chain or chains. As many of the chain pairs as may be required for suitable conveyance will be provided.

In their travel through the machine section of Figure 1, the liners first come beneath a hold-down bar 13 which is spaced inwardly from the ends of the liners. The ends of the liners initially come above the end of a guide or sweep 14 which is curved or shaped so as to turn the ends of the liners over above the bar 13 as shown in Figure 3. At a further position in the path of travel of the liners the bar 14 is relieved as at 14a so that another bar 15 which engages beneath the turned over end of the liner can raise this end up until it occupies the vertical position shown in Figure 4. It will be noted in this figure that the upraised end of the liner is substantially confined between members 15 and 14a, and further that the liner is somewhat humped about the outer edge of the bar 13. Thus, without producing such frictional relationships between the liner and the various bars as would interfere with the conveyance of the liner in its path of travel, the liner mouth is nevertheless closed or pinched, as it were, along a line spaced from the actual end of the liner.

The liner mouth is now in a position to be opened up as shown in Figure 5. This may be done, in one mode of operation, by means of an air blast issuing from a nozzle 16, and it will be noted in this figure that the actual mouth of the liner is opened up while the liner walls adjacent the mouth are kept closed by their configuration around and against the bars 15, 14a and 13. It is not necessary that the liner mouth be opened up throughout the length of the end of the liner nor opened up to any extent greater than sufficient to permit the insertion of a nozzle 17 which initially lies above the mouth of the liner in the position shown in Figure 5, but when the liner has been opened as shown, is moved downwardly into the liner mouth as shown in Figure 6. The position of the nozzle as initially inserted will be substantially that shown in Figure 7. But the liner is moving in the direction of the arrow in that figure, and it is my object to cause the nozzle to introduce into the liner a quantity of sealing substance which will be substantially evenly distributed throughout the length of the liner mouth and which will not fail to be applied in proper quantity, and even in excess at the ends of the liner mouth. This is illustrated in Figure 8 where the introduced sealing substance 18 is shown continuous across the width of the liner and as deposited in some excess at the ends, as at 19 and 19a. To attain this,

as soon as the nozzle has been introduced into the liner mouth it is swung forwardly into the position shown in the dotted lines in Figure 7 at 17a. This causes a generous application of the sealing substance to the forward end or corner of the mouth of the liner. Then during the travel of the liner in the direction of the arrow, the nozzle is swung backwardly until at the conclusion of the application step it occupies the position shown at 17b in Figure 7, insuring the application of sealing substance to the trailing end or corner of the liner mouth. Finally the nozzle is tilted forwardly again until it occupies the position shown at 17c in Figure 8, whereupon it is withdrawn so as not to interfere with the forward movement of the liner. Mechanism for accomplishing these movements of the nozzle will hereinafter be described; but the procedural features which I have just outlined insure a proper initial distribution of the sealing substance. I have indicated diagrammatically in Figures 6 to 8 a valve 20 to control the flow of sealing substance through the nozzle. It will be clear that the flow will not be initiated until after the nozzle is inserted in the mouth of the liner and that it will be terminated prior to the withdrawal of the nozzle. The volume of the sealing substance passing through the nozzle in a given length of time will be controlled either by the valve 20 or by other means.

As indicated, I may use any desired sealing substance irrespective of the nature of the liner walls and irrespective of their coated or uncoated condition. In other words, the selection of the sealing substance can be based upon the function which it is to perform, and without regard to whether or not it is suitable for use as a precoating substance for the material of the liners. I may employ adhesives which are rendered tacky by means of a solvent and which set through the evaporation of the solvent. I may use adhesives which set up through the application of heat; but for most uses, I prefer to apply a sealing medium which is thermoplastic in its character, which may be applied in a liquid, semi-liquid or pasty condition effected through temperature, which in the condition of application will form a strong adhesive union with the walls of the liner and which, due to cooling, will set rapidly to provide the desired hermetic seal.

After the sealing medium has been applied, I prefer further to distribute it by the application of pressure to the walls of the liner. This may not in all instances be necessary; but it assures, first, that the sealing medium will contact the surfaces to be joined throughout an unbroken line across the mouth of the liner, second, it may be employed to spread the adhesive throughout desired areas of the surfaces to be joined so as to provide a seal of very considerable area, and third, it may be caused to produce particular configurations in the adhesive to promote the efficiency of the seal. Thus, as indicated in Figures 8 to 10 inclusive, I may employ rollers as pressure members, which rollers have grooved contacting surfaces. The rollers are indicated at 21 and 22 and their surfaces are shown grooved so that the application of pressure not only forms a film of the sealing substance 23 between the walls of the mouth of the liner, but also forms a thickened rib or bead 25 extending across the mouth of the liner. The showing in the figures is somewhat exaggerated and it will be understood that the quantity of sealing substance ordinarily employed is such as to form a thin film at 23. The pro-

vision of a bead is thus a matter of additional insurance, especially at the points of plural thickness along the area of the longitudinal seam.

As shown in Figures 14 and 15, the same kind of insurance of adequate sealing at the ends of the mouth of the liner can be obtained by providing the rolls 21 and 22 with raised operating portions 21a and 22a which are of slightly lesser length than the length of the mouth of the liner, and by timing these rolls with the travel of the liner in such a way as to produce at the ends of the mouth thereof beads as shown at 27 and 28.

When the end closure has been completely formed, a pair of guide members 29 and 30 may be employed to return the upraised end of the liner to the horizontal position as shown in Figure 12. Figure 13 shows one end of a sealed liner, thelapping parts of the longitudinal seam being indicated at 31.

The beads 25, 27 and 28 hereinabove described are, I find, useful in rapidly effecting a tight seal; but they may be eliminated and the walls of the mouth of the liner between which the sealing substance has been applied may merely be pressed together in such a way as to produce adhesion and distribute the sealing substance in the form of a film between the areas of the liner to be joined together. Pressing rollers are not the only pressing means which may be employed. In Figures 25 to 28 inclusive I have shown another form of means comprising a pair of endless chains 32 and 33 arranged horizontally so as to pass around pairs of sheaves or sprockets 34, 35 and 36, 37. One at least of each of these pairs of sprockets will be driven. Where the chains approach each other they are arranged to travel with the liner ends; but the sprockets 35 and 37 are spaced further from each other than the sprockets 34 and 36 so as to provide a gradual pressing action. The chains themselves bear brackets or the like 38 and 39 in Figures 27 and 26 to which actual pressing means 40 may be attached. I prefer to provide these pressing means with headed studs 46 which pass through holes in the ears or brackets and which bear tension springs 47 engaging at one end of the head of the stud and engaging at the other end the bracket 38 or 39. This structure permits the pressing means 40 to follow the path of travel of the liner even though the chains have begun to diverge therefrom about the sprockets 34 and 36, until the pressing members are actually pulled away from the liner mouths by the brackets. The pressing members may, if desired, be grooved as at 48.

As already indicated, the sealing medium will usually be applied in a warm, plastic and adhesive condition, and the function of the pressing members beyond that of distributing the sealing medium between the liner walls will normally be that of cooling and setting it. Where, however, a further plasticizing of the extruded sealing medium is required, it is not beyond the spirit of my invention to apply heat to the pressing elements, or to incorporate electric heaters in them. And for some purposes, I may employ more than one set of pressing elements, one group being heated and the other unheated. Where desired, the pressing elements may be specially cooled.

For most fabrics used in the production of bag tubes, I have found that the air blast from the nozzle 16 is sufficient to open up the mouth of the liner to permit the insertion of the nozzle 17. In instances where the material of the bag tube is extremely flimsy in its character, or where the cutting means tends to burr the materials, or

where for any other reason the edges of the mouth of the bag tube may tend to adhere together, it may be desirable to provide more positive means for opening up the bag tube mouths. Several of such means have been indicated in Figures 16 to 21. In Figures 16 and 17 I have shown a pair of rollers or discs 49 and 50. These discs have enlarged portions 49a and 50a which contact the liner mouth during its movement. These enlarged portions may be coated or covered with a pressure sensitive material which, adhering to the walls of the liner mouth, pull them apart as shown in Figure 17 as the rolls rotate. After the liner mouth has been thus opened, the pressure sensitive substances pull away from the liner mouths as shown. The pressure sensitive coating can conveniently be applied to the surfaces of renewable tapes 51, 52, removably fastened in some suitable fashion to the disc enlargements 49a and 50a.

A variant mechanism and procedure is illustrated in Figure 18, where discs 53 and 54 are provided with extending means 53a and 54a which contact the liner walls as the discs rotate. Before they contact the liner walls, these raised areas are adapted to contact the surfaces of rolls 55 and 56 to which a suitable adhesive has been applied and which in turn apply this adhesive to the raised surfaces 53a, 54a.

In Figures 19 and 20 I have shown a mechanism employing frictional contact with the liner walls to open up the liner mouth. The operation of this mechanism is based upon the fact that if the juxtaposed liner walls are frictionally engaged on each side by opposed means, and the means moved relative to each other so as to effect a relative displacement of the walls, these walls, by reason of their interconnection at the end of the liner mouth, will be caused to separate as indicated in Figure 20. I employ for this purpose a pair of rotating discs or rolls 57 and 58 which have extended frictional contacting surfaces 57a and 58a. I may provide frictional contacting surfaces of the same radius and drive them at different speeds, or if it is more convenient to arrange the shafts bearing rolls 57 and 58 to rotate at the same speed, I can gain my effect by employing a different effective radius for the frictional contacting members 57a and 58a, which produces a different effective linear speed of these elements.

For relatively heavy and stiff fabrics for the walls of the liner, a retarding means which first engages and retards the leading end of the liner mouth and then presses down on the top of the up-turned liner mouth will effect a positive opening. I have illustrated this in Figure 21 where on a suitable bracket 59 I have mounted an arm 60 bearing a contacting roller 61. A stop 62 may be provided on the bracket to limit the downward motion of the arm, and the weight of the arm may be relied upon to open up the liner mouth 1a, or the arm may be spring pressed, as is desired.

As hereinafter set forth in connection with a particular machine embodiment, I may also employ vacuum members to open up the liner mouths.

In Figures 22 and 23 I have indicated a mechanism for closing the ends of liners, embodying a number of the features hitherto described. Like parts have been given like index numerals and will not be redescribed. The chains which move the liners are indicated at 5a and 6a. The machine is built on a suitable standard or base 63, and alongside the path of travel of the ends of

the liners it bears a bracket 64. On this bracket in fixed position there is mounted the air nozzle 16 for the air blast to open the liner mouths, where this expedient is employed. The nozzle is connected by a conduit 65 to a valve 66 which in turn is connected by a conduit 67 to a reservoir or pressure equalizer 68. A pump 69 which may be driven by a motor 70 is connected to the pressure equalizer.

In the figures I have shown a main drive shaft 71 which will be driven by a suitable prime mover, not shown. This shaft bears a bevel gear 72 meshing with another bevel gear on a horizontal shaft 73 journaled in a bracket 74. The shaft 73 carries a cam 75 against which the operating rod 76 of the valve 66 may ride. By these means it is possible to time the turning on and off of the air blast through the nozzle 16 with the movement of liners through the machine.

It will be noted that the shaft 71 by means of bevel gears 77, a short shaft 78 and bevel gears 79, drives the sprocket 80 over which the chain 5a passes. A similar mechanical arrangement, not detailed in the drawings, may be employed to drive the sprocket 81 over which the chain 6a passes.

On the bracket 64 I mount a vertically slidable head 82. On this head, on a shaft 83 there is mounted the nozzle 17 for the sealing substance. The head 82 is moved up and down in guideways on the bracket 64 by means next to be described. A lever 84 is pivoted on the frame of the machine at one end as shown at 85. At its other end it is connected to the head 82 by a link 86. Intermediate the ends of the lever 84 I pivot a rod 87 which may be suitably guided on the frame of the machine as at 88, and bears at its lower end a cam follower 89. This cam follower contacts a cam 90 on a horizontal shaft 91 which is journaled in a bracket 92 on the machine frame. The shaft 91 is connected with shaft 71 by a bevel gear arrangement 93. The shape of the cam and the timing of the elements is such that just after the leading end 1a of a liner passes the nozzle 17, the nozzle 17 is lowered into the mouth of the liner which has been opened up by the air blast. The nozzle 17 is raised to clear the liner mouth just before the trailing end of the liner mouth passes the position of the nozzle.

To feed the nozzle I have shown a tank 94 mounted on the bracket 64 and containing the sealing substance 95. A weight-like plunger 96 located above the sealing substance is intended by me to indicate that the sealing substance will be under pressure so that its delivery to the nozzle will be insured. The tank 94 may be provided with electrical heating means 97. A valve 98 is in connection with the tank 94 and is coupled to the nozzle 17 by a flexible conduit 99. In some instances it may be desired to heat this flexible conduit and I have diagrammatically shown an electrical heating means surrounding it at 100.

In order to control the flow and timing of the sealing substance through the operation of the valve 98, I connect this valve by means of a rod 101 to a cam follower 102 bearing against a cam 103 mounted, in the exemplary embodiment, directly upon the shaft 71.

In order to accomplish the swinging movement of the nozzle which has hereinabove been described and is best illustrated in Figure 7, I mount a pinion 104 on the nozzle bearing shaft 83. This pinion meshes with the teeth of a rack 105 slidably mounted in brackets or the like on the head

82. Springs or other means 106 tend to maintain the rack 105 in such a position that the nozzle 17 will be vertical; but it will be seen that if the rack 105 is moved downwardly or upwardly the nozzle 17 will swing in a clockwise or counter-clockwise direction. The rack 105 terminates downwardly in a cam follower 107. A cam 108 having a cam groove 109 is mounted on a shaft 110 journaled in a bracket 111 on the frame of the machine. This shaft is connected by a bevel gear arrangement 112 with the main drive shaft 71. The cam groove 109 is not co-extensive with the periphery of the cam 108. When the head 82 is up-raised, carrying the nozzle 17 to its inoperative position, the cam follower 107 is not engaged by the cam at all. But when the head 82 is lowered, the cam follower 107 enters the cam groove 109 and the swinging motion described in connection with Figure 7 is accomplished by the shape of the cam groove 109 as the cam follower rides in it during a portion of the revolution of the cam 108.

I have shown the pressing rollers 21 and 22 in the mechanism of Figure 22. The roller 22 is mounted directly upon a shaft 113 journaled in a bracket 114 on the machine frame. The shaft is connected by a bevel gear arrangement 115 with the main drive shaft 71. At its upper end the shaft 113 bears a pinion 116 which meshes with the pinion 117 on another shaft 118. This latter shaft is journaled in an arm 119 which is pivoted as at 120 to the bracket 114 (see Figure 24). The shaft 118 bears the roller 21. The shafts 113 and 118 may be connected by a tension spring 121 by means of which the rollers 21 and 22 may be caused to exert the desired pressure on the liner mouth.

I have thus far described a machine which employs the principle of my invention in effecting an end closure in liners of bag tube form. Normally such liners will then be deposited upon carton or container blanks which may then be tubed about the liner. This produces a lined carton and container, which may be made as such by the box manufacturer and shipped to the box user. The bag will normally have been adhered to a plurality of the carton walls. It will be evident to the skilled worker in the art, in the light of the teachings herein made, that the mechanism of Figures 22 and 23, with the addition of simple means to move the carton flaps out of the way, may be employed to seal an end of a bag tube which is already in a carton and adhered to the walls thereof.

The carton user will square up or erect the carton, thus erecting the bag therein, will close the carton on one end and will thereafter fill it, effect a hermetic seal in the bag mouth, and close the carton on the other end. Many lined cartons however, instead of being provided with bags closed at one end, are provided merely with liners open at both ends, and of tubular form. The carton user will erect these cartons, seal one end of the liner, close the same end of the carton, and then fill, seal and close the other end, as above described. I shall now set forth a mechanism embodying the principle of my invention and useful both for sealing one end of a squared up bag after it has been filled and for sealing of the end of a bag tube in a carton. I shall describe in this connection such mechanism as is employed for effecting the hermetic seal in the liner. Such mechanism may be adapted to a wide variety of carton handling machinery. I prefer to employ such a machine as is set forth in the

copending application of myself and Van Guelpen, Serial No. 450,704. In these machines erected cartons are caused to travel in a fixed path by means of a conveyor and during their travel their orientation is changed from time to time so that fixed folding members may operate upon the various flaps of the carton to effect the closure thereof. In the last mentioned application, the carton bodies are carried along preferably in cages on the conveyor which grip them externally and maintain them in proper position to be acted upon by the various instrumentalities. Suitable cages for holding unfilled, unsealed and unclosed lined cartons in operative position and also for holding lined cartons which have been sealed and closed at one end and have also been filled, are shown in detail in the said application. Such cages are diagrammatically indicated in the drawings hereof but have not been fully detailed and are not herein described at length.

The machine of the said application can be so operated that unfilled and unsealed cartons are placed in alternate ones of the cages while filled cartons are placed in the remainder for making the final seal in the liner and for closing the top of the carton. The apparatus hereinafter described is applicable to such an operation also, and it will be sufficient to the skilled worker in the art to point out that the mechanism may be used to seal either end or both ends of a liner tube.

Referring first to Figures 29 to 36 inclusive, I have shown therein in a diagrammatic form a series of operations and instrumentalities suitable for the operations referred to. A carton 122 is shown as having a tubular liner 15. The flaps of the carton have been bent down out of the way and will be suitably held by means in the machine while operations are proceeding on the liner. The carton may be thought of as traveling in the direction of the arrow. A pair of spreader fingers 123 and 124 enter the open end of the liner with a downward movement and then spread apart as shown in Figure 30 to elongate or fishtail the liner mouth. When this occurs, the elongated condition of the liner mouth may be maintained by a pair of rods 125 while the spreader fingers 123 and 124 are moved toward each other and withdrawn from the mouth of the liner. For the spreading means I may use any of those mechanisms detailed in the said patent and application referred to above. During the further travel of the carton, the spread end of the liner comes between a pair of members 126 and 127. These members are shown in Figure 31 as suspended by arms 128 and 129. The entire mechanism shown in Figures 31 to 36 may be thought of as moving with the carton during its travel. The first action is that of the arms 128, 129 in bringing the members 126 and 127 against the flattened mouth of the liner so as to pinch it together along a line interspaced from the end of the liner mouth. This pinching relationship will be maintained until after the sealing substance has been introduced into the liner mouth and distributed; and its purpose is to prevent sealing substance from passing beyond the pinch line established by members 126 and 127.

Next, vacuum members 130 and 131 come against the sides of the liner mouth above the pinch line. The vacuum is caused to be effective and the members 130, 131 are swung slightly away from each other whereby to open up the

mouth of the liner. Figure 33 shows the nozzle 17 introduced into the mouth of the liner after it has been opened up in this fashion. The vacuum members 130 and 131 have been swung out of the way.

Figure 34 shows the mouth of the liner after the sealing substance has been introduced therein and the nozzle 17 withdrawn. The sealing substance is diagrammatically indicated at 132. In my structure I preferably employ the members 126 and 127 not only as pinching members but as pressing members for distributing the sealing substance. They may be grooved as at 133 or otherwise as may be desired. Their next action is illustrated in Figure 35 where means not there shown but hereinafter described, have caused the members 126 and 127 to swing upwardly until they are substantially parallel and are exerting pressure against the seal to produce the effects hereinabove set forth. Figure 26 illustrates the relationship of the parts after the seal has been completed and after the members 126 and 127 have released the liner.

In the remainder of the figures I have detailed a portion of a machine embodying mechanism for performing these operations. The machine comprises a frame 134 on which a conveyor 135 is mounted. This conveyor bears spaced turrets 136 which in turn carry the cages 137 to which reference has already been made. A part of the machine is shown, and the remainder of it will preferably have means for closing the carton flaps. Such means are not germane to the present invention. I have indicated a machine drive comprising a motor 138 and a gear box 139 by means of which a vertical shaft 140 is driven. This shaft may bear an end sprocket 141 for the conveyor chain 135. The upper end of the shaft is journaled in an upper frame structure 142 where it is connected by a bevel gear arrangement 143 to a stub shaft 144 bearing a sprocket 145. A chain 146 passes over this sprocket and another sprocket 147 on a stub shaft 148. An interspaced stub shaft 149 is provided on the upper frame of the machine. The shafts 148 and 149 bear sprockets 150 and 151 over which passes a chain 152. This chain bears at intervals spreader assemblies 153 in the form of a housing to which the spreader fingers 123 and 124 are mounted. To operate these spreader fingers, I provide a cam track 154 in which is engaged a cam follower 155. This cam follower is pivotally connected to the upper ends of the fingers 123 and 124 which fingers are slotted in the particular embodiment shown. Pins at the end of the housing 153 pass through these slots and the result of the movement of the cam follower 155 is to impart to the spreader fingers downward, outward, inward and upward motions which have already been described.

The stub shaft 149 also bears a gear 156 which meshes with a gear 157 on another shaft 158. This shaft also bears a heart shaped cam 159. A plunger 160 is slotted where it passes over the shaft 158 and carries a pair of cam followers 161 and 162 bearing against the cam 159 at opposite sides thereof. A uniform translational movement is thus imparted to the plunger 160 which goes forward and returns once for each revolution of the shaft 158.

A shaft 163 is mounted on the upper framework of the machine and carries a pinion 164 with which a rack 165 meshes. This rack is bolted or otherwise attached to the plunger 160. The shaft 163 also bears another pinion 166 which

meshes with a rack 167 slidably mounted in brackets or slide bearings 168 and 169 on the upper framework of the machine. The timing of the mechanism is such that the rack 167 moves with a carton in the direction of the arrow in Figure 37 for a certain distance, and then moves back in time to come into the same relationship with a succeeding carton and move forward with it. To this rack I attach the operating instrumentalities which were referred to in connection with Figures 31 to 36. This is accomplished by attaching to the rack 167 (Figures 39 and 44) a pair of arms 170 and 171. These arms are connected by a plate 172, and if greater support is desired, the plate 172 may be caused to ride on one or more rollers 173 pivoted on a stationary bracket 174 on the main machine frame. A pair of shafts 175 and 176 extend between the arms 170 and 171 and are journaled therein. The members 126 and 127 are suspended from these shafts by the arms 128 and 129 of which there are counterparts at each end of the members 126 and 127. The suspending arms 128 and 129 are fixed on the shafts 175 and 176 so that as these shafts rotate, the arms can swing the elements 126 and 127 to the respective positions shown in Figures 31 and 32. Beyond the arm 170 the shafts 175 and 176 bear pinions 177 and 178. These pinions in turn mesh with a pair of intermediate pinions 179 and 180 mounted on studs on the arm 170. Shaft 175 is thus tied to shaft 176 in such a manner that the two shafts will rock equally and in opposite directions when either is actuated. To actuate the shafts, I provide a rack 181 (Figure 41) meshing with pinion 177 and held in that position by a bearing member 182. This rack in turn is connected with a plunger 183 which extends to the other side of the rack 167 and bears a cam follower 184 contacting a cam 185 fixed on the upper framework 142 of the machine. Since the cam track is stationary, but the cam follower moving due to the movement of rack 167, it will be seen that the plunger 183 will be moved by the cam and that the shafts 175 and 176 will be rocked to accomplish the pinching and releasing movements on the part of members 126 and 127 in proper timed relationship.

It is not desired to move these members during the return stroke of the rack 167. To this end, instead of mounting the cam follower 184 directly upon the plunger 183, I mount it to an arm or pair of arms 186 which in turn are pivoted to the plunger. The arm or arms bears a stop 187 and is controlled by a spring 188. On the forward stroke of the rack 167 the arm or arms 186 come into general alignment with the plunger 183, and the rack is operated. On the return stroke the arm or arms 186 assume the position shown in Figure 40 and become inoperative to move the rack. The plunger 183 will be controlled by a spring 189 and will preferably be provided with stop means 190 impinging against the rack 167.

Continuing with the description of the mechanism for operating the members 126 and 127, it will be noted that these members are not only suspended by the arms 128 and 129 but also have connected with them other arms 191 and 192, which are pivoted to the pinching and pressing members at a point remote from their pressing edges. There is one of the arms 191 at each end of the member 126 and one of the arms 192 at each end of the member 127. Each pair of arms 75 is connected respectively with a lever 193 or 194.

These levers are fixed to a shaft 195 which passes between the arms 170 and 171. It will be understood from Figure 42 that as the shaft 195 turns in a counterclockwise direction, the lever arms 193 or 194 will pull upwardly on the arms or links 191 and 192 and will swing the members 126 and 127 from the position shown in Figure 34, for example, to the position shown in Figure 35. To operate the shaft 195, as best shown in Figures 39 and 42, I affix to it a pinion 196 which meshes with a rack 197. This rack bears a cam follower 198 which, as shown in Figure 40, is of the same character and has the same type of mounting as the cam follower 184. The cam follower 198 contacts and is operated by a stationary cam 199 on the upper framework of the machine.

The vacuum members 130 and 131 are mounted by means of depending arms from sleeves 200 and 201 which surround the shafts 175 and 176. They could be mounted on separate shafts between the arms 170 and 171, but the sleeve construction just described is a more convenient one. These sleeves as shown in Figure 43, bear pinions 202 and 203 which mesh with connecting pinions 204 and 205 mounted on studs on a channel shaped sheath 206 suspended from the sleeves. A rack 207 engages with the pinion 202 and extends beyond the rack 167 to bear a cam follower 208 engaging a stationary cam 209 on the upper framework of the machine. As shown in Figure 40, the cam follower 208 has a similar mounting for a similar purpose as that described in connection with cam follower 184.

From the description thus far, it will be evident that as the rack 167 moves, it carries with it the several instrumentalities and their operating agencies, and that these instrumentalities are caused to perform the functions illustrated in Figures 31 to 36 through the agency of the stationary cams 185, 199 and 209, as the instrumentalities travel with the cartons.

The bracket 174, as has already been pointed out, is stationarily affixed to the main frame of the machine. It may bear a valve 210 connected by a conduit 211 to a vacuum pump and motor indicated at 212 and 213. The valve in turn is connected by a flexible conduit 214 and branch conduits 215 and 216 to the vacuum means 130 and 131. The plunger 217 of this valve may pass through the bracket 174 and engage directly and be operated by a cam 218 (Figure 44) which is mounted on the plate 172 which connects the arms 170 and 171. This plate is moving, so that the cam can operate the valve 210, the valve of course being stationary on bracket 174.

I mount a head 219 in such manner as to be vertically reciprocable on the bracket 174. On this head I mount a hollow shaft 220 which is connected to a valve housing 221. The valve housing bears the nozzle 17. In the valve housing there is a valve plunger as at 222 in Figure 46 and its actuating rod 223 passes through the head 219. It may be drawn to closed position by a compression spring 224 engaged between the head and a washer 225 on the operating rod. To move the operating rod, I mount a lever member 226 pivotally on a part 227 of the bracket 174. This lever member has an elongated contacting surface for the operating rod 223 of the valve, since the valve rod goes up and down with the head while the lever does not. The lever is fulcrumed as at 228 in Figure 39. Beyond the fulcrum it is pivoted to a rod 229 which passes through a hole in the bracket 174. This rod bears a cam follower 230

which is pivoted to the rod 229 and carries a stop as shown. It is that kind of a cam follower which will be operated by a cam when moving in one direction but not in the other. It will of course have a spring control (not shown). It is operated by the cam 231 affixed to the plate 172.

In order to move the head 219, and therefore the nozzle 17, up and down, the head is connected by a link 232 to a lever arm 233 fixed to a shaft 234 journaled on the bracket 174 (see Figure 45). One end of the shaft 234 bears another lever arm 235 which at its end carries a cam follower 236. This cam follower is designed to ride in a cam track 237 formed in members 238 on the plate 172. There is a side cam track 239 connected with the main cam track 237 by angularly related portions, and the junctures of the main and side cam tracks are provided with switches 240 and 241. The purpose of this construction is to permit the side cam track 239 to bring about a lowering of the head while the operating mechanisms are traveling with the carton, but to return the follower in track 237 so that no lowering of the head occurs on the return stroke.

To bring about the swinging movement of the nozzle 17 illustrated in Figure 7, I employ a construction somewhat similar to that described in connection with Figure 23. On the hollow shaft 220 of the nozzle I mount adjacent the head 19 a pinion 242. This meshes with a rack 243 slidably mounted on the head 219 and urged to a neutral position in which the nozzle 17 is vertical by means of springs 244 and 245. This construction is shown in Figure 45. The rack 243 bears a rigid outwardly extending rod 246 which carries a cam follower 247, as shown in Figure 44. Cam follower 247 which is engaged by cam members 248 and 249 affixed to the plate 172. The shape of these members can best be appreciated from Figure 38 where between them they form a track 250 within which the cam follower 247 is adapted to be engaged, but only when the head 219 is in lowered position. This will occur of course only during the travel of the cam plate 172 and its associated mechanism with the carton in the forward direction of the machine. On the return traverse, when the head 219 is raised, the cam follower 247 will lie above the member 248, as shown in Figure 44.

In Figure 37 I have shown, supported above the machine on the upper frame member 142, a tank or reservoir 251 for sealing substance 252. Again I have indicated diagrammatically electrical heating means 253 and a plunger 254 indicative of the fact that the sealing substance is maintained under some pressure. The reservoir is connected to the valve 221 by a flexible conduit or a conduit a portion of which is flexible as at 255. Electrical heat may be applied to the conduit or a portion thereof as diagrammatically indicated at 256.

As already indicated, the machine last described may be employed to form closures in either end of a bag tube. In one operation on such a machine erected, tubular lined cartons, may be run through and sealed and closed on the bottom end. Then they may be returned to the machine after filling and the upper closure of the liner made together with the closure of the upper flaps. Or filled and unfilled cartons may be run through the machine engaged in alternate cages. The machine embodies means for folding down the upstanding sealed mouth of the liner as at 256 in Figure 37, and thereafter has means for folding over and closing (or sealing, if desired) the carton flaps.

Modifications may be made in my invention

without departing from the spirit of it. Having thus described my invention, what I claim as new and desire to secure by Letters Patent is:

1. A method of hermetically sealing the end of a flexible tubular bag or liner which comprises pressing together opposite walls thereof whereby to hold them against each other along a line spaced from the end of the liner, opening up the liner end so as to separate the said walls beyond the line of pressure and introducing a sealing medium into said open end in a continuous body to form a plastic, ribbon-like mass whereby to effect a seal above the line at which said walls are held together.

2. The method of claim 1 wherein the sealing medium as so introduced is a thermoplastic adhesive capable of forming a firm bond with said walls, and is in a heat-softened condition.

3. The process claimed in claim 1 wherein the introduction of sealing medium is carried on progressively along the line at which said walls are held together whereby to distribute it substantially evenly along said line.

4. The process claimed in claim 1 wherein the introduction of sealing medium is effected progressively along the line at which said walls are held together, whereby to distribute it substantially evenly along said line, and wherein the said walls above the said line are thereafter pressed together whereby to effect a further distribution of said sealing medium therebetween, and to produce a wider area of sealing.

5. The method of sealing an end of a flexible tubular bag or liner, which comprises bringing together opposite walls thereof along a line spaced from the liner end, and pressing said walls together along said line, opening up said liner end beyond said line of pressure, inserting a nozzle therein, causing a plastic sealing medium to extrude from said nozzle in a continuous ribbon, and moving the nozzle relative to said bag end so as to distribute said continuous ribbon of sealing medium within the liner end adjacent to said line of pressure, and substantially coterminous therewith.

6. The process claimed in claim 1 wherein the said bag or liner is in motion during the introduction of adhesive therein and wherein the said nozzle is first introduced into the liner end, moved forwardly in the direction of motion of the liner to deposit sealing medium at the leading terminus of the liner and then moved backwardly to apply the medium along said line of pressure and at the trailing terminus thereof, then moved forwardly to accommodate the motion of the liner, and finally withdrawn therefrom.

7. The process claimed in claim 1 wherein the said bag or liner is in motion during the introduction of adhesive therein and wherein the said nozzle is first introduced into the liner end, moved forwardly in the direction of motion of the liner to deposit sealing medium at the leading terminus of the liner, then moved backwardly to apply the medium along said line of pressure and at the trailing terminus thereof, then moved forwardly to accommodate the motion of the liner, and finally withdrawn therefrom, and in which after the introduction of said sealing medium, the said walls above the first mentioned line of pressure are pressed together so as to effect a further distribution of said sealing medium, and to produce a wider area of sealing.

8. A process of sealing the mouths of flexible tubular bags or liners which comprises juxtaposing and pressing together the walls along a line

across the liner spaced from the actual mouth thereof, separating said walls above said line of pressure, introducing a sealing medium therein in a continuous body so as to form a plastic, ribbon-like mass, again juxtaposing said walls and spreading said medium by outside manipulation above the line of pressure whereby to insure a continuous adhesive juncture between said walls, extending fully across said liner.

9. In a machine for the purpose described, means to press together opposite wall portions of a liner or the like along a line across said portions but spaced from the ends thereof to prevent the downward displacement flow of an adhesive substance introduced therein, means to separate said wall portions beyond said line of pressure, and means to introduce between said wall portions an adhesive substance in a continuous body and in a condition to bond with said wall portions, so as to form a plastic, ribbon-like mass for effecting a seal above said line of pressure.

10. In a machine for the purpose described, means to press together opposite wall portions of a liner or the like along a line across said portions but spaced from the ends thereof, means to separate said wall portions beyond said line of pressure, and means to introduce between said wall portions an adhesive substance in a continuous body to form a plastic ribbon-like mass, and in a condition to bond with said wall portions, and means for imparting to said last mentioned means movement with respect to said wall portions whereby to deposit said adhesive substance along said line of pressure.

11. In a machine for the purpose described, means to press together opposite wall portions of a liner or the like along a line across said portions but spaced from the ends thereof to prevent the downward flow of an adhesive substance introduced therein, means to separate said wall portions beyond said line of pressure, and means to introduce between said wall portions an adhesive substance in a continuous body to form a plastic ribbon-like mass, and in a condition to bond with said wall portions, and means for imparting to said last mentioned means movement with respect to said wall portions whereby to deposit said adhesive substance along said line of pressure, and means for pressing the separated wall portions together after the introduction of said adhesive therebetween to distribute said adhesive and widen the area of sealing.

12. In a machine for closing the open end of a tubular liner means for moving the liner in a path, means to press the walls thereof together along a line adjacent to but spaced from the liner end, means for opening up the liner end beyond said line of pressure, nozzle means for introducing an adhesive into said opened liner end in a continuous body so as to form a plastic ribbon-like mass, and means for manipulating outside surfaces of the liner end thereafter so as to distribute the plastic adhesive therein.

13. In a machine for sealing the open end of a liner included in a carton, means for moving the carton in a path and in erected condition, spreading means for entering the end of the liner and acting to spread and flatten it, means traveling with the carton to press the flattened walls of the liner together along a line of pressure adjacent but spaced from the liner end, means for opening up the liner end beyond the line of pressure, nozzle means for introducing into said liner end a sealing adhesive in a continuous body so as to form a plastic, ribbon-like mass, and means for

21

pressing the liner end after the introduction of adhesive therein, said means acting to displace said adhesive so as to insure the formation of a complete seal all across the liner opening.

14. In a machine for sealing the end of a tubular liner, means for pressing together the walls of said liner adjacent but spaced from the end thereof, means for opening up the end of said liner beyond the line of pressure thereon, a head, a nozzle rockably mounted on said head, and a cam means to actuate said nozzle to cause said nozzle to enter the open end of said liner, to rock while in said liner, and to be withdrawn therefrom, a connection between said nozzle and a source of supply of adhesive substance, valve means, means to actuate said valve means in

22

time with the movement of said nozzle to cause said adhesive to issue in a continuous body from said nozzle while said nozzle is in said liner, and means acting to press the area of said liner beyond said line of pressure after the withdrawal of said nozzle to distribute the adhesive therein, said cam means being configured to cause said nozzle to enter the end of said liner, to rock forwardly in the direction of motion of the liner to deposit adhesive at the forward corner of the liner end, to rock rearwardly during the further motion of the liner to distribute adhesive along the line of pressure therein to the rear corner thereof, then to rock forwardly and be withdrawn.

SAMUEL BERGSTEIN.
